FIGURE TRAY

John A. Rench, 416 E. North St., Lima, Ohio

Filed July 14, 1958, Ser. No. 51,759

Term of patent 14 years

(Cl. D44—10)

FIG-1

FIG-2

FIG-3

FIG-4

Figure 1 is a perspective view of the figure tray, embodying my new design;

Figure 2 is a top plan view thereof;

Figure 3 is a vertical sectional view indicated by line 3—3 of Figure 2; and,

Figure 4 is a transverse sectional view taken along line 4—4 of Figure 2.

The characteristic features of my design reside in the seven fanciful animal shaped cavities shown entwined among themselves in the relationship as shown within the perimeter of a mold of conventional depth.

I claim:

The ornamental design for a figure tray, as shown and described.
